SAFETY RAZOR

Joseph Muros, Cambridge, Mass., assignor to
 Gillette Safety Razor Company, Boston, Mass.,
 a corporation of Delaware

Application February 28, 1945, Serial No. 580,106

12 Claims. (Cl. 30—60)

This invention relates to safety razors of the type in which a flexible, replaceable blade is supported in position for shaving between co-operating blade-clamping members. It comprises an improved razor having a hinged one-piece cap so operated as to clamp the blade by centrally applied pressure on the blade-seat of the razor.

The improved safety razor of my invention is a one-piece razor in the sense that it includes in its organization no loose parts which are likely to become lost or mislaid when the razor is opened for the purpose of cleaning or replacing a blade. It is also characterized by a one-piece cap constructed and arranged to clamp the blade by centrally-applied pressure as distinguished from pressure applied at the corners of the cap. Uniform supporting action of the blade-engaging faces of the clamping members upon the interposed blade is thus insured and tendency to bridge it obviated.

The attempt has been made heretofore to provide safety razors operating in this manner but in constructions heretofore used it has been necessary to employ a blade having an aperture in its body large enough to permit passage of the cap in endwise position. This involves an objectionable weakness in the blade as well as objectionable long motion of the parts in opening the razor. On the contrary, the razor of my invention is compact and self-contained in construction and may employ blades of any commercial construction, including double-edged blades of the well-known "Gillette" type.

An important feature of my invention consists in a clamping spindle having threads formed at two different places in its length, one being effective for opening and closing the cap and the other being effective for moving the cap to clamp the blade interposed between it and the blade-supporting member. Preferably and as herein shown, these two threads are of different pitch; the thread for opening and closing the cap being a quick thread of steep pitch and the thread for clamping the blade being of finer pitch and so well adapted for developing adequate clamping pressure. As herein shown, the two threads are constructed and arranged for successive operation; that is to say, the quick thread is effective for opening or closing the cap, while the clamping thread is disengaged, and the fine thread is effective for the clamping operation while the quick thread is disengaged.

Another feature of the invention consists in convenient provision for adjusting the opening angle of the cap. As herein shown, the train of

mechanism for opening and closing the cap includes a distance piece or spacer operating with a predetermined but adjustable amount of clearance between two shoulders or abutments. These shoulders are arranged for relative adjustment and their place in the train of mechanism is such that the greater the amount of separation between them the greater is the angle of cap opening.

Still another feature of the invention consists in an organized safety razor structure including a hinged single-piece cap arranged to be operated as above set forth, in which the whole structure when once assembled and adjusted is maintained as an operative organization by a single screw inserted as the last step in the assembling operation.

These and other features of the invention will be best understood and appreciated from the following description of a preferred embodiment thereof, selected for purposes of illustration and shown in the accompanying drawings in which:

Fig. 1 is a view in perspective of the complete razor in closed condition;

Fig. 2 is a view of the razor in vertical section and on an enlarged scale.

Fig. 3 is a view in longitudinal section corresponding to Fig. 2, except that the razor is shown in its opened condition;

Fig. 4 is a corresponding view in longitudinal section at right angles to that of Fig. 3;

Fig. 5 is a view in perspective of the cap member of the razor;

Fig. 6 is a view in perspective of the spider and cap member;

Fig. 7 is a view in perspective of the blade-supporting or guard member and handle of the razor; and

Fig. 8 is a view in perspective showing the spider and cap-operating members of the razor in exploded relation.

The razor herein shown is designed particularly to handle double-edge blades of the well known "Gillette" type having a longitudinal medial slot with several local enlargements therein, and reentrant corner notches which define elongated unsharpened end portions in the blade. It will be understood, however, that the razor may be adapted for handling other types of blades by appropriate modification of its design, all within the scope of the present invention.

The razor herein shown comprises a blade-supporting or guard member 10 substantially rectangular in outline and presenting a blade-seat convex in contour, upon which the blade is trans-

versely flexed when it is clamped in place. The longitudinal edges of the guard member are curved downwardly and longitudinally slotted to provide guard bars 11 therein. The body of the guard member is provided centrally and symmetrically with a diamond-shaped depression 12 which stiffens the guard as a whole. As best shown in Fig. 7, the member 10 is further stiffened by having both of its ends down-turned in the form of flanges 13. Slots 14 extend inwardly through these flanges and through the longitudinal vertices of the diamond shaped depression 12. The flanges 13 and the body of the guard member are also provided with a pair of slots 15 located near the rear edge of the guard member and with a pair of rectangular clearance apertures 16 located near the front edge of the guard member. The member 10 is perforated centrally in the bottom of the diamond-shaped depression 12 to receive the upper end of the razor handle 17 and this is headed or upset in the perforation to form a permanent connection between the handle and the guard member.

Co-operating with the guard member 10 is a hinged, one-piece cap member 18 similar in outline and somewhat narrower than the guard member and having an inner concave blade-engaging face which is the complement in contour to the convex face of the guard member. At its rear edge the cap 18 is provided with a pair of downwardly extending arms 19 which merge into rearwardly extending branches 20 and each of these terminates in an inwardly extending lug 21. In its forward corners, the cap 18 is provided with reinforcing corner-lugs 22 adapted to fit with clearance into the apertures 16 of the guard member when the cap is brought into clamping relation therewith.

Centrally, the cap 18 is provided with a rounded boss disposed concentrically with respect to a threaded hole 23 therein. The cap 18 is pivotally connected or hinged at one edge to a spider which will now be described. This comprises a central bar 24 having down-turned arms 25 at both ends merging into parallel transverse bars 26. The bar 24 serves as blade-locating means in the razor and the blade is slotted to fit the bar. The arms 25 of the bar pass downwardly through the slots 14 in the guard member 10 at the vertices of the depression 12. A pivot 27 extends inwardly through one end of each of the transverse bars 26 and through the arm 19 of the cap at the point where the axis of the arm 19 intersects the axis of its rearward branch 20. The hinged cap 18 is free to swing on the pivots 27, being limited at times in its movement by the guided contact of its vertical arms 19 with the slots 14 of the guard member. The central bar 24 of the spider is formed integral with a hollow hub 28 at the upper end of a hollow stem 29 having a fine external thread 30 near its lower end. The stem 29 is of such diameter as to slide freely within the hollow portion 17 of the razor handle. The slot of the blade is provided with a central enlargement of circular outline to receive the hub 28.

In the assembled razor, a circular nut 31 is screwed upon the thread 30 and forms in effect an adjustable shoulder on the stem 29. The stem 29 and spider are movable up and down in the razor assembly to effect both clamping and swinging movement of the cap 18 as will be presently described.

A sleeve 32 fits loosely outside the hollow stem 29 of the spider and serves as a spacer or dis-

tance piece between the nut 31 and a shoulder provided by the lower end of the handle 17 thus limiting the highest position to which the spider can move, as shown in Fig. 4. A compression spring 33 surrounds the sleeve 32, bearing at its lower end on the nut 31 and at its upper end against the shoulder provided by the handle 17 and urging the spider always downwardly. The handle is shouldered externally to receive the barrel 34 to which it is permanently united, as by a forcing fit. The barrel encloses the stem 29, the sleeve 32 and the spring 33 as well as a clamping spindle 35 disposed concentrically within the stem 29. The spindle 35 is of such diameter as to turn freely in the stem 29 and is provided with a threaded upper end 36 arranged to make clamping engagement with the central threaded hole 23 of the cap and thus to transmit centrally-applied clamping pressure to the cap when desired. The spindle is moved longitudinally by a coarse or quick thread 37 formed on its exterior and engaging with a corresponding internal thread cut in the interior of the stem 29 of the spider. This thread 37 is much coarser than the clamping thread 36 on the end of the spindle.

At its lower end the spindle 35 is provided with a pair of spaced shoulders 38 and is connected below the end of the barrel 34 to a thimble 39 rotatable upon the barrel and fitting snuggly thereon. Near its lower end the barrel is slotted to receive a flat segmented key 40 which projects inwardly from the wall of the barrel between the shoulders 38 of the spindle and so positively limits its longitudinal movement, the spindle being shown in its lowermost position in Figs. 3 and 4.

A screw 41 having a threaded shank 42 is screwed into the end of the spindle 35 and provided with a circular head which fits the end of the thimble 39. A dowel pin 43 makes positive connection between the lower end of the spindle and an annular flange within the thimble 39, these parts being held together by the screw 41. It will be seen that the thimble 39 provides convenient means for the user to rotate the spindle 35 for raising or lowering the spider, swinging the cap and also for clamping or releasing the cap.

The razor is assembled from the parts above described as follows: The cap 18 and the spider are first connected as shown in Fig. 6 by the pivots 27, and the blade-supporting member 10 is permanently connected to the handle 17-34. The cap is now turned up into a vertical position so that the rearward branches 20 of the arms 19 extend downwardly and the stem 29 of the spider is inserted in the bore of the barrel, the branches 20 at the same time passing down through the slots 15 of the blade-supporting member. After the branches 20 are passed through the slots, the cap is swung into its closed position, thus permitting the spider to move downwardly to its lowest position. The razor is then inverted while the cap is held in place and the sleeve 32 and the spring 33 are dropped into place between the barrel 34 and the stem 29 of the spider.

The circular nut 31 is next dropped into the end of the barrel, engaged with the thread 30 of the spindle 29, and screwed in by the use of a spanner until it is adjusted properly for the desired opening of the cap. The angle of opening of the cap is determined by the position of the nut 31. The upward movement of the spider is

positively arrested when the sleeve 32 is engaged between the shoulder of the handle 17 and the nut 31. It will be seen that the farther up on the stem 29 the nut 31 is screwed, the more is the upward movement of the stem 29 confined, and consequently the smaller the opening angle of the cap 18. On the other hand, as the nut 31 is turned reversely so as to increase the upward movement permitted to the stem 29 the greater is the opening angle permitted to the cap. The spindle 35 is now inserted in the bottom of the barrel and screwed inwardly until the collars 38 at its lower end span the slot for the key 40 at the lower end of the barrel. The key 40 is now put in place in the barrel and projects inwardly between the two shoulders of the spindle. The thimble 39 is then placed on the end of the barrel and turned to bring the dowel pin 43 into alignment with the hole prepared for it in the end of the spindle. When these have been brought into registration the screw 41 is set up tightly in the end of the spindle thus holding the thimble in place, which in turn holds the key 40 against the possibility of removal. The key 40 is shown in Fig. 8 as having a wing at each end which prevents it from passing wholly through the barrel while locating the inner portion of the key in position to be engaged by the collars 38 of the spindle.

Starting with the cap in open position as shown in Fig. 4, the razor above described is used in the following manner: In the open position of the cap, the blade-seat of the blade-supporting member 10 is fully exposed and the transverse bars 26 of the spider are initially lifted above the level of the blade-seat. A blade 44 which, as already explained, is slotted to receive the bar 24 and the hub 28 of the spider, may now be freely placed in the razor and will rest at its ends upon the bars 26 of the spider, all as shown in Fig. 4. The angle of cap opening is determined by the height of the spider and the engagement of the inturned lugs 21 on the arms 20 of the cap with the under-side of the blade-supporting member 10. As the spindle 35 is now turned in a clock-wise direction the thread 31 lowers the spindle rapidly and permits the spring 33 to force the spider downwardly. In the downward movement of the spider, the arms 19 of the cap engage shoulders in the blade-supporting member adjacent to the slots 15 and the cap is accordingly swung toward and into its closed position. When the arms 19 of the cap have assumed vertical positions they are free to pass downwardly through the slots 15 of the guard member.

At substantially the same time that the cap reaches its closed position, the quick-thread 37 of the spindle 35 passes above the internal thread of the spider stem 29 and the clamping thread on the end 36 of the spindle is free to enter the threaded hole 23 of the cap. After this occurs, further turning of the spindle draws down the cap with a centrally-applied pressure, flexing the blade 44 upon its blade-seat and clamping it in shaving position as shown in Fig. 2.

After the razor has been used, the series of steps above set forth occur in their reverse order. First, the spindle 35 disengages the cap 18 without any substantial movement thereof, that is to say, pressure of the cap on the blade is released by a slight vertical movement, but no swinging movement of the cap takes place. The vertical movement imparted to the cap by the threaded end 36 of the spindle is sufficient for

the purpose of adjusting the edge exposure of the blade to the preference of the user. After the disengagement of the threaded end 36 from the cap, the quick-thread 37 engages the internal thread of the stem 29 of the spindle. Further rotation of the spindle 25 now raises the spider against the action of the spring 33, lifting the transverse bars 26 above the level of the blade-seat, so that the blade is lifted from the blade-seat, and at the same time causing the cap 18 to swing toward its open position by carrying the pivots 27 up through the slots 15 while the inwardly extending lugs 21 are engaged against the underside of the blade-supporting member. The limit of upward movement of the spider occurs when the nut 31 brings up against the bottom of the spacing sleeve 32, as shown in Figs. 3 and 4.

It will be understood that the spring 33 and also the weight of the moving parts both tend at all times to lower the spider 24 and thus automatically to close the cap 18. The actual up-and-down position of the spider and the position of the cap 18 are controlled by the spindle through its threaded connection 37 with the stem of the spider. It will be further understood that there is sufficient clearance to free the spindle completely after one thread is disengaged so as to facilitate engagement of its other thread.

Having thus disclosed my invention and described in detail an illustrative embodiment thereof, I claim as new and desire to secure by Letters Patent:

1. A safety razor having a blade-supporting member, a one-piece cap hinged to swing toward and from said member and having a centrally disposed threaded hole, a spring acting to close the cap, and a threaded clamping spindle movable first to control the spring closing of the cap and then to engage the threaded hole of the cap and to clamp the cap by centrally applied pressure against a blade on said blade-supporting member.

2. A safety razor having a blade-supporting member, a spider movable with respect to said member, a one-piece cap hinged to the spider to swing toward and from said member and having a central aperture, a spring acting to move the spider and cap into closed position, and a spindle for counteracting the action of said spring and for engaging the aperture of the cap to clamp the cap by centrally applied force against a blade on said blade-supporting member.

3. A safety razor having a blade-supporting member provided at both ends with slots, a spider movable with respect to said member, a one-piece cap pivotally connected to the spider and having arms passing through the slots of said member and a central aperture, and a spindle operatively connected to the spider for controlling the up and down movement thereof while the cap is locked against swinging by the guided movement of its arms in the slots of the blade-supporting member, and having a portion shaped to engage the aperture of the cap for clamping the cap by centrally applied pressure against a blade on said blade-supporting member.

4. A safety razor having a blade-supporting member, a co-operating one-piece cap, and a clamping spindle having a steep-pitch threaded connection with the blade-supporting member and a fine-pitch threaded connection with the cap constructed and arranged to be successively operated.

5. A safety razor having a guard member, a

blade-supporting spider movable therein, a co-operating blade clamping cap, and a spindle having threaded connection with the spider and a threaded connection with the cap, said connections being constructed and arranged to be successively engaged in clamping a blade between the cap and guard members.

6. A safety razor having a blade-supporting member, a co-operating one-piece cap hinged for opening and closing movement toward and from said blade-supporting member and movable bodily to exact blade-clamping pressure, and a clamping spindle having two screw threads thereon, one for opening or closing the cap and the other for clamping the cap upon a blade interposed between it and the blade-supporting member.

7. A safety razor having co-operating blade-clamping members, one of which comprises a one-piece cap hinged to swing about one edge, and means for opening and closing the cap including a distance piece and abutments relatively adjustable to vary the angle of cap opening.

8. A safety razor having co-operating blade-clamping members, one of which comprises a one-piece cap hinged to swing about one edge, a spring acting at all times to swing the cap into closed position, and a spindle having a threaded connection opposing the closing action of the spring arranged to disengage when the cap is closed and a separate threaded clamping connection with the cap arranged to engage after the cap has been closed.

9. A safety razor having a blade-supporting member, a one-piece cap hinged to swing into closed position above said member, a spring tend-

ing at all times to close the cap, and a spindle having a threaded connection for holding the cap open against spring pressure and being rotatable to permit the cap to close under the actuation of the said spring.

10. A safety razor having co-operating blade-clamping members, one of which comprises a one-piece cap hinged to swing about one edge, a spring acting to swing the cap into closed position, and a spindle having spaced threads thereon, one thread acting to swing the cap open against spring tension, and the other thread acting to move the cap in a rectilinear path for clamping or releasing a blade interposed between the said clamping members.

11. A safety razor having a guard member fast to a tubular handle, a spider carrying a hinged one-piece cap and having a hollow stem movable within said tubular handle, a spindle concentrically disposed within said stem and having a threaded connection therewith, a spring normally depressing the spider, a lost-motion connection between the handle and spindle, and a threaded connection between the spindle and said cap.

12. A safety razor having a blade-supporting member, a one-piece cap hinged at one edge thereof and being adapted to swing toward and from the said supporting member, a spring acting to close said cap, a clamping spindle co-operating with said cap to clamp the same by centrally applied force against a blade on said blade-supporting member, and means associated with said spindle to counteract the action of said spring.
